UNITED STATES PATENT OFFICE.

JOHN T. STONEY, OF CLEVELAND, OHIO.

MOLDING-MACHINE.

1,343,940.

Specification of Letters Patent. Patented June 22, 1920.

Application filed February 11, 1914. Serial No. 818,018.

To all whom it may concern:

Be it known that I, JOHN T. STONEY, a citizen of the United States, residing at Cleyland, in the county of Cuyahoga and

5 State of Ohio, have invented a certain new and useful Improvement in Molding-Machines, of which the following is a full, clear, and exact description.

This invention relates in general to molding machines, and more particularly to apparatus for supporting a molding table in such position that it may be adjacent a jarring table or platform which is raised and lowered by any means, and may also be re-15 moved from such platform at will.

The invention further includes mechanism whereby the molding table may be raised and lowered, and mechanism whereby the molding table may be rolled over.

20 Generally speaking, the invention comprises the elements and combinations thereof set forth in the accompanying claims.

Reference should be had to the accompanying drawings forming a part of this specification, in which Figure 1 is a front elevation of the machine in section; Fig. 2 is a side elevation with parts of the machine in section; Fig. 3 is a top plan view of the machine with parts in section; Fig. 4 is an elevation with parts in section, showing a detail of the locking mechanism for the table; Fig. 5 is an elevation with parts in section taken at right angles to the showing in Fig. 4; Fig. 6 is a front elevation; Fig. 7 is a side elevation with portions in section of a modified form of machine; Fig. 8 is a side elevation of a portion of a still further modified form of machine; and Fig. 9 is an elevation partly in section, showing a detail of construction of the machine shown in Fig. 8.

The machine of my invention is arranged so as to be movable with respect to the usual jarring and raising table, and therefore may be removed after the mold is drawn from the pattern, thus leaving free space in which to operate, for the removal of the mold from the jarring table.

In the accompanying drawings, there is indicated at 1 a table or platform which may be raised or lowered in any desired manner. It is common in the art to operate such a platform as I have shown at 1 by means of compressed air cylinders, thus permitting

the table 1 to be continuously raised or lowered within certain limits, or permitting the table to be quickly moved up or down, or jarred.

I have not shown any mechanism for operating the table 1, inasmuch as this mechanism forms no part of my invention, and as before stated, any desired form of such mechanism may be used.

The device of my invention is intended to coöperate with such a table or platform, as represented at 1.

The whole apparatus is usually contained within a pit such as represented at 2, for the apparatus is so bulky that it would otherwise be necessary for the workmen to operate upon a platform. It has been found more convenient to sink the apparatus below the level of the working floor and permit the men to work upon the floor. The pit is covered by means of a platform 3, which will need no further description.

At 4 there is indicated a molding table which is adapted to support the flask which is generally represented at 5. This table 4 has side arms 4^a, which are mounted upon trunnions 6. These trunnions extend through journal blocks 7, which are mounted in a head piece generally represented at 8, and shown in Fig. 2. This head piece comprises sides 8^a between which the journal block 7 is mounted, and the length of the side pieces 8^a is such that the journal block 7 may have a certain amount of vertical movement relative to the head 8. These arms 8^a are secured at their upper portions by means of a cross bolt 8^b.

The heads 8 are supported at the upper end of vertical supports 9,—these supports being mounted in standards 10. The standards are so formed as to provide a guide for the supports 9, insuring their moving in a vertical direction when it is desired to lift the molding table.

Upon trunnions 6 there are flanged wheels 6^a, these wheels being secured to the trunnions thereby to turn as the wheels turn. Secured to the wheels 6^a is one end of the flexible element or cable 6^b, which flexible element at its opposite end is secured to the standard 10. When table 4 is raised the pulley or cable 6^b upon wheels 6^a will cause them to turn and so roll over the table 4. The reverse of the operation just described

takes place when table 4 is subsequently lowered.

There is sufficient loose play in the flexible element 6^b so that the roll over molding 5 table may move with the jarring platform.

The standards 10 are mounted upon a platform 11, and the supports 9 may extend through suitable openings provided in the platform 11, and if of necessity the 10 supports 9 are sufficiently long, depressions 12 may be provided in the floor of the pit, to accommodate the supports.

The supports 9 may be raised by various forms of mechanism,—one of which forms is 15 shown in Figs. 1 and 2, which will now be described.

The platform 11 carries two upright supports 13, which at their upper ends form journals that receive a transverse shaft 14. 20 This shaft forms a pivot upon which is mounted a lever construction.

The forward end of this lever construction provides outwardly extending arms 15, the arms preferably being formed of structural 25 members which are suitably united to form a rigid and strong structure. Upon the ends of each of the arms are carried end pieces 16 which are forked as clearly shown in Fig. 2, the forked portion being substantially 30 rectangular and forms a mounting for blocks 17, which blocks may freely slide in the rectangular forked portions of the members 16.

The blocks 17 are carried upon pins 18, which pins are mounted upon collars 19, 35 that are adjustably secured upon the supports 9. As will be apparent, these collars 19, by their adjustment may be caused to elevate the molding table to a greater or less extent when the arms 15 are raised or lowered.

The arms 15 are secured to a sleeve 20 which is supported upon a shaft 14. Extending rearwardly from the sleeve 20 are arms 21, which at their extreme ends are 45 provided with journals that receive a shaft 22, this shaft being held by collars 22^a carried upon the ends thereof and outside of the arms 21.

Upon the shaft 22, and upon that portion 50 between the arms 21, there is mounted a block 23, the block forming a journal for the shaft 22. This block is mounted in a head 24, the head having top and bottom pieces which confine the block 23, so that the block may slide longitudinally with respect to these sides. The sides 24^a are secured to end pieces 24^b which are in the form of sleeves, the sleeves being mounted to slide upon vertical rods 25. These rods 55 60 25 at their upper ends are secured by a cross-head 26.

The head 24 is mounted upon a piston rod 26, which extends within a cylinder 27 and is united to a piston 28. The cylinder and piston 65 are of proper construction to be

worked by means of compressed air, or by steam, which finds an entrance and exit by the port 29.

The mechanism which has heretofore been described as mounted upon the platform 11, 70 is preferably adapted to be shifted as a unit with respect to the table or platform 1. This may be accomplished in various ways, and for the purpose I have shown the platform 11 as forming the upper portion of a 75 car mounted on suitable wheels indicated at 11^a, the wheels being mounted on tracks 11^b, which are suitably secured at the bottom of the pit 2.

The rear end of the platform 11 is provided with an overhanging member 30, which is secured to the end of a piston rod 31. This piston rod extends within a cylinder 32, and cooperates with a piston therein, which piston may be operated in the cylinder by means of compressed air or steam, 80 which operation, as will be clear, will cause the platform of the car to be moved forwardly or backwardly according to the direction in which the piston within the cylinder 32 is driven.

The operation of the device is as follows: The molding table 4 is adapted to receive a flask such as indicated at 5, the molding table also having a pattern plate attached thereto which lies within the flask 5. Sand is poured into the flask 5 and the table 4 is allowed to rest upon the jarring platform 1. With things thus arranged the jarring table is operated, and due to the manner in which 95 the trunnions of the table 4 are mounted with respect to their supporting means, the table 4 may have a limited amount of movement which will be amply sufficient to jar with the platform 1. When the jarring is 100 complete a board is placed upon the top of the flask, and suitable means is employed to hold the board to the flask. The supports for the table are elevated, and the table 4 is rolled over either by hand or by the mechanism described for this purpose.

When the table is rolled over the platform 1 is raised until it engages the lower end of the upturned flask. The flask is then released from the table 4, and the table 1 115 lowered, which draws the mold from the pattern. When the platform 1 has been lowered the molding table and its supports, together with the mechanism for operating the supports, is bodily moved with respect 120 to the platform 1, and the mold resting thereon, so that the space above the mold is entirely free and unobstructed, and the mold can readily be removed from the platform 1 by means of a crane or any suitable apparatus for the purpose.

In Figs. 6 and 7 I have shown a modified form of mechanism for mounting the trunnion of the roll-over table, and the mechanism for directly raising and lowering these 130

trunnions. The car platform is the same as that shown previously, as represented at 11. At each side of the platform 11 is a vertical upright portion 40, which, at its upper end, 5 carries two vertically extending posts 41. These posts at their upper end are joined by a brace 42.

A trunnion block 43 is provided with openings which engage with the rods 41 and 10 slide upon the same. These trunnion blocks carry the trunnion 44 upon which one end of the roll-over table 4' is mounted.

The shaft 44 is engaged by the head 45 of a link 46, the head being provided with a 15 central opening which is slightly elongated so that the head of the link may have a certain amount of play with respect to the shaft 44. This play permits the table to be raised and lowered when in contact with a 20 jarring table, as previously described, and the jarring action will not interfere with nor cause the operation of the raising and lowering mechanism.

The link 46 is pivotally connected with 25 an arm 47 which would correspond with such an arm 15 as shown in Fig. 3. It will be understood that the arm 47 is supplemented by another similar arm, and these arms will be constructed in a manner similar to and function similar to the arms 15, as 30 shown in Fig. 3.

The advantage of the construction shown in Figs. 6 and 7 lies in the fact that there is no necessity for constructing depressions in 35 the pit, such as illustrated at 12, to receive the supporting rods which extend into these pits when the table is in its lowermost position.

Figs. 8 and 9 disclose a form of machine 40 similar in the main to the machine shown in Figs. 1 and 2, but differing in the form and arrangement of the motor for operating the mechanism for raising and lowering the roll-over table.

45 The rear end portion 21 of the lever construction has pivotally secured thereto a piston rod 50. This piston rod cooperates with a piston within the cylinder 51. The cylinder is provided with trunnions 52 that are 50 mounted in journal boxes carried by the frame of platform 11, as shown in Fig. 9.

This construction provides a pivotal mounting for the cylinder 51 and allows the cylinder to move with respect to lever 21. 55 The cylinder is supplied with motive fluid by means of a suitable flexible supply conduit.

Having thus described my invention, what I claim is:

60 1. In a molding machine, the combination with a platform adapted to be raised and lowered, of a roll over molding table unit adapted to coöperate with the said platform, said roll over molding table unit 65 comprising a roll over molding table, trun-

nions upon which the table is supported, and means for raising and lowering the molding table, and means for removing the molding table and its mechanism bodily as a unit relative to and away from the said platform 70 to leave a free, unobstructed space above the platform.

2. In a molding machine the combination with a platform adapted to be jarred and also adapted for raising and lowering to 75 draw the pattern from the mold, a molding table adapted in one position to coöperate with the said platform for jarring and in another position to coöperate with the platform for drawing the pattern, trunnions on 80 which the molding table is mounted, guiding and supporting means for the trunnions, means for bodily shifting the molding table, trunnions and guiding means therefor relative to said platform.

3. In a molding machine, the combination with a platform adapted to be jarred and also adapted to be raised and lowered for drawing a pattern of a roll over molding table, adapted in one position to coöperate with the platform for jarring and in another position to coöperate with the platform for drawing a pattern, trunnions upon which the table is mounted, guiding and supporting means for the trunnions, 90 means for raising and lowering the molding table and means for bodily shifting the molding table, trunnions, guiding, and supporting means, and the raising and lowering means for the table bodily relative to 100 the platform.

4. In a molding machine combination with a platform adapted to be jarred and adapted to be raised and lowered for drawing a pattern, of a molding table, adapted in one position to coöperate with the platform for jarring, and in another position to coöperate with the platform for drawing a pattern, trunnions upon which the molding table is mounted, supporting and guiding means for the trunnions, means for raising and lowering the molding table, means for rolling over the molding table as it is raised and lowered, and means for moving the molding table and its mechanism bodily 110 relative to said platform.

5. In a device of the character described, the combination with a roll over molding table, trunnions upon which the table is mounted, supporting means for said trunnions, a supporting platform upon which the supporting means is mounted, operating rods for raising and lowering the trunnions, a pivoted lever mechanism for operating the said rods; one part of said lever mechanism being operatively connected with the raising and lowering rods, a power device engaging the other end of said lever mechanism, the lever mechanism and power device being carried upon the supporting plat- 125 130

form above mentioned, and means for moving the said platform.

6. In a molding machine, the combination with a molding table, trunnions upon which the table is mounted, guiding and supporting means for the trunnions, a platform adapted to be raised and lowered and to receive and draw the mold from the pattern, and means for removing the molding table and its mechanism bodily as a unit relative to and away from the said platform to leave a free unobstructed space above the platform.

7. In a molding machine, the combination with a molding table, trunnions upon which the table is mounted, guiding and supporting means for the trunnions, a platform adapted to be raised and lowered, and to receive and draw the mold from the pattern, suitable guides which coöperate with the molding table and its mechanism whereby said table and mechanism may be bodily as a unit moved relative to and away from said platform to leave a free unobstructed space above the platform.

8. In a molding machine, the combination with a platform, adapted to be raised and lowered, of a roll over molding table, adapted to coöperate with said platform, trunnions upon which the table is mounted, means for raising and lowering the molding table, and means for bodily as a unit laterally moving the molding table and its mechanism away from the platform to leave a free, unobstructed space above the platform.

9. In a molding machine, the combination with a platform, adapted to be raised and lowered, of a roll over molding table, adapted to coöperate with the first mentioned platform, trunnions upon which the roll over table is mounted, guiding and supporting means for the trunnions, and means for moving the molding table and its mechanism bodily and as a unit in a lateral direction, with respect to and away from the platform, thereby to leave the platform unobstructed in a vertical direction.

10. In a molding machine, in combination a platform unit comprising a platform and means for moving said platform up and down, a table unit comprising a roll-over molding table, trunnions upon which the molding table is mounted, supports for the trunnions, a base upon which the supports are mounted, and means whereby the table unit may be bodily moved as a unit with respect to the platform unit to leave a free unobstructed space above the said platform.

11. In a molding machine, the combination with a platform member, adapted to be raised and lowered, of a roll over molding table member and mechanism for operating said table member adapted to coöperate

with the platform member in drawing the pattern from the mold, said members and associated mechanism, as units, being relatively movable away from each other, to leave a free, unobstructed space above the platform.

12. In a molding machine, the combination with a platform member, adapted to be raised and lowered, of a molding machine member, adapted to be raised and lowered, and to coöperate with the platform member in drawing the pattern from the mold, said members being as units relatively movable away from each other in a lateral direction, thereby leaving the space above the platform member free and unobstructed.

13. In a molding machine, the combination with a platform member, adapted to be jarred, of a molding machine member, adapted to be raised and lowered, to coöperate with the said platform in drawing the pattern from the mold, and to be jarred with the platform, a base upon which the molding machine member is mounted, said molding machine member and base therefor being relatively movable as a unit with respect to the platform member to leave a free and unobstructed space above the platform.

14. In a molding machine, the combination with a platform member, adapted to be jarred, of a molding table member, adapted to be raised and lowered, to coöperate with the platform member to draw the pattern from the mold, and adapted to be jarred with the platform, said members being relatively movable in a lateral direction to leave the space above the platform member free and unobstructed.

15. In a molding machine, the combination with a platform member, adapted to be raised and lowered, of a molding table member, adapted to coöperate with the platform member, to receive and draw the pattern from the mold, supporting means upon which the molding table is mounted, and means whereby said supporting means and parts carried thereby may be moved away from the platform member, thereby to move the molding table and leave a free and unobstructed space above the platform member.

16. In a molding machine, the combination with a platform adapted to be jarred and to be raised and lowered to draw the pattern, a roll over molding table adapted to be raised and lowered, supporting means upon which the molding table is pivotally mounted above the said platform and to roll over above said platform, said means including a lost motion connection whereby the molding table is adapted to be jarred with the platform member, and means whereby the supporting means and molding table may be moved as a unit relative to the

platform to leave a free unobstructed space above the platform.

17. In a molding machine, the combination with a platform, adapted to be raised and lowered, of a roll over molding table unit comprising a molding table, adapted to coöperate with the platform to receive and draw the mold with respect to the pattern, trunnions upon which the table is mounted, also supporting means for said trunnions, means for raising and lowering the trunnions, and a support which is independent of said platform upon which the molding table and its coöperating elements are mounted, whereby the molding table unit may be moved to leave a free and unobstructed space above the platform.

18. In a molding table, the combination with a platform adapted to be jarred, of a molding table unit, said molding table unit comprising a molding table adapted to be jarred with the platform, trunnions upon which said table is mounted, supporting means for the trunnions including a loose connection, means for lowering and raising the trunnions, and a support upon which the molding table and its coöperating elements are carried, and means whereby the molding table unit may be moved relative to the platform to leave a free unobstructed space about the platform.

19. In a molding machine, the combination with a platform, adapted to be jarred, of a molding table member, adapted to be jarred with the platform, trunnions upon which the table is mounted, supporting

means for the said trunnions, operating rods for raising and lowering the trunnions, said operating rods having a loose connection with the trunnions, and a pivoted lever mechanism operatively connected with the raising and lowering rods, a power device engaging one end of said lever mechanism, a support upon which the molding table and its coöperating elements are mounted, said support being movable to provide a free and unobstructed space above the platform.

20. In a molding machine, the combination with a platform member, adapted to be raised and lowered, of a molding table, adapted to be raised and lowered with the platform, trunnions upon which the table is mounted, supporting means for said trunnions, operating rods for raising and lowering the trunnions, a pivot lever mechanism for operating the said rods, one part of said lever mechanism being operatively connected with the raising and lowering rods, a power device engaging another part of the lever mechanism, a supporting platform upon which the molding table and its coöperating elements are carried, means for moving said supporting platform, relative to the first mentioned platform, thereby providing a free and unobstructed space above the first mentioned platform.

In testimony whereof, I hereunto affix my signature in the presence of two witnesses.

JOHN T. STONEY.
